UNITED STATES PATENT OFFICE.

JAMES L. HEARING, OF COLUMBUS, OHIO.

FLOOR-SCRAPER.

No. 909,406.

Specification of Letters Patent.

Patented Jan. 12, 1909.

Application filed April 4, 1908. Serial No. 426,184.

To all whom it may concern:

Be it known that I, JAMES LEROY HEARING, a citizen of the United States, residing at Columbus, in the county of Franklin and State of Ohio, have invented a certain new and useful Improvement in Floor-Scrapers, of which the following is a specification.

The particular object of this invention is to provide an improved device for scraping or dressing wooden floors to remove rough places or old polishings preparatory to sandpapering and polishing or repolishing them.

The invention is embodied in the construction herein shown and described and then particularly pointed out in the claims, the invention not being confined in its embodiment to the particular instance of it herein exemplified.

In the accompanying drawings—Figure 1 is a side view with parts in section and parts broken out; Fig. 2 is an elevation of the forward end of the device; Fig. 3 is a detail illustrating the means for preventing the threaded tool shank from turning in its holder; Fig. 4 is a sectional detail illustrating the means for pivoting the tool holder; Fig. 5 is a sectional detail illustrating the means for adjusting the angular relation of the scraping blade to the tool shank.

20 In the views 6 designates the main frame. The forward portion of the frame is supported by a pair of wheels 7, 7 preferably rubber-tired. These wheels 7, 7 are journaled on stud spindles 8^a, 8^a of a U-shaped axle 8. Projecting upward from the axle 8 are two stout pins 9, 9 that extend through holes in the forward part of the main frame.

10, 10 are stout coiled springs around the pins 9, 9 and between the axle and the main frame. The pins 9, 9 and therefore the axle are held from dropping out by means of fastening pins 11, 11. The springs 10, 10 yield to pressure on the forward part of the frame.

45 The rear portion of the main frame is supported by a single wheel or roller 12. This roller has a round shank 12^a on which is pinned a collar 12^b and the frame is suitably bored to receive said shank. The upper part of said boring is of the same diameter as the shank, while the lower part is enlarged forming a socket 13 to receive a coil spring 14 that encircles the shank between the collar 12^b and the upper end of 55 the socket. The shank 12^a is secured in place by means of a keeper plate 15 perforated for

the passage of the shank and for screws 15^a to secure it to the under side of the frame. The shank and roller thus have a swiveled connection with the frame but the frame 60 can be depressed on the shank.

16 designates the tool holder. This holder consists of a tube oscillatory supported in the frame between the front and rear wheels on stud bearings 17, 17 turned on the ends 65 of screw bolts 17^a, 17^a, said bolts being threaded into holes in opposite sides of that portion of the frame through which the holder extends.

18 designates the scraper blade. This 70 blade as shown consists of a rectangular piece of sheet steel so that two opposite edges can be used. The blade is secured by means of a thumb-screw 19 to a base 20 that is pivoted at 21 to the shank 22. A piece of 75 rubber 23 can be interposed between the blade and the base if desired.

24 is a thumb-screw threaded through the shank and swiveled in the base 20 for adjusting the angular relation of the blade to 80 the shank. The shank 22 is threaded, as seen at 22^a, and extends up through the holder tube 16. To keep the shank 22 from turning in the holder it is provided with a lateral pin 22^b (see Fig. 3) that projects into 85 a slot 16^a in the tube. The slot 16^a permits adjustment up or down of the scraper shank in its holder. The scraper shank is held in the position to which it is adjusted by means of nuts 25 and 26 threaded tightly on the 90 shank above and below the tube; but interposed between the lower nuts 25 are washers 27 and 28 between which is held the forward end of a leaf spring 29 the rear end of which works against the lower side of the 95 main frame. The scraper is shown to be set at an incline to the direction in which the machine is to be moved.

30 designates a handle for operating the device. This can be secured by suitable 100 means on any of several holes 31 in a brace on the back of the frame and to a rod 32 hinged to a fin on the tail of the frame, said rod being provided with small holes 32^a. The holes 31 and 32^a permit a large range of 105 adjustment of the handle.

In practice, as is usual with floor scrapers of this general type, the device is pushed forward to perform the scraping operation. But it will be observed first, that in my machine the frame yields to pressure at both 110 the front and rear, second, that the scraping

2
tool is intermediate these yielding points, and third, that the scraper yields backward so that the action of the scraper is very much like that given a scraper in the human hands. The scraping action of the tool can be made heavy or light at the will of the operator; and hard places do not endanger the tool because it has a yielding action rearward independent of the pressure applied by the operator.

10 What I claim and desire to secure by Letters Patent is:

1. In a floor scraper, the combination of the main frame, and forward and rear supporting means for the same, a holder 16 pivoted in said frame between said supporting means to oscillate in a vertical plane, a threaded tool-receiving shank adjustable on said holder, and nuts on said shank for retaining the same in adjusted position in said holder.

2. In a floor scraper, the combination of the main frame, and forward and rear supporting means for the same, a holder 16 pivoted in said frame between said supporting means to oscillate in a vertical plane, a threaded tool-receiving shank adjustable in said holder, nuts on said shank for retaining the same in adjusted position, and means to prevent the turning of said threaded shank.

3. In a floor scraper, the combination of the main frame, means for supporting said frame at its forward and rear ends, a holder pivoted in said frame between said supporting means to oscillate in a vertical plane, a tool-receiving member movable up and down in said holder, means for securing the same in adjusted position, and a spring tending to press the tool-receiving portion of the

tool-receiving member toward the forward 40 end of the main frame.

4. In a floor scraper, the combination of the main frame, means for supporting said frame at its forward and rear ends, a holder pivoted in said frame between said supports 45 to oscillate in a vertical plane, a tool-receiving member movable up and down in said holder, means for securing the same in adjusted position, and a spring tending to press the tool-receiving portion of the tool- 50 receiving member toward the forward end of the main frame, the means for securing the tool receiving member being also adapted for securing in position one end of said spring.

5. In a floor scraper, the combination of the main frame, means for yieldingly supporting said frame at its forward and rear ends, a scraping tool pivoted in said frame between said supporting means to oscillate 55 in a vertical plane, and a spring tending to press the scraping tool toward the forward end of the machine.

6. In a floor scraper, the combination of the main frame, means for yieldingly supporting said frame at its forward and rear ends, a holder pivoted in said frame between said supports to oscillate in a vertical plane, a tool-holding member adjustable in said holder, and a spring tending to press 70 the lower end of the tool-holding member toward the forward portion of the main frame.
